UNITED STATES PATENT OFFICE.

HENRY EMERSON WETHERILL, OF PHOENIXVILLE, PENNSYLVANIA.

STAMPING DEVICE.

Application filed August 30, 1924. Serial No. 735,109.

To all whom it may concern:

Be it known that I, HENRY EMERSON WETHERILL, a citizen of the United States, residing at Phoenixville, in the county of 5 Chester and State of Pennsylvania, have invented certain new and useful Improvements in a Stamping Device, of which the following is a specification.

My invention relates to a rubber stamping device to which I have given the trade name, "Typen." This invention particularly relates to a device adapted to be held in one hand and moved over the surface to be printed or written upon, and operated to bring any desired type into stamping position; a further object is to provide a novel means for spacing the device as it is moved over the surface to be printed and to provide various indicating means by which certain type may be selected by the sense of touch; and a still further object is to provide a device which may be manufactured at a low cost.

Referring to the drawing; Fig. 1, is a side elevation of the device. Fig. 2, is a rear elevation of Fig. 1; Fig. 3, is a front elevation of Fig. 1; Fig. 4, is a vertical sectional view on line 4—4 Fig. 2, and Fig. 5 is a perspective view showing the lower portion of the frame.

Referring to the accompanying drawings in which like reference characters refer to like parts, 1 represents a disk having the type 2 mounted upon its periphery. The disk 1 is mounted upon a shaft 3 which is rotatably and slidably mounted in a sleeve 5 secured in a frame 6.

The frame 6, consists of a spring metal plate having formed at the lower portion thereof a foot plate 7, which is adapted to rest upon the surface of the paper or other article upon which the device is to be used. The foot plate is bifurcated forming two members 8 and 9, with a space 12 between them, which space permits one type on the disk 1 to be pressed between the members 8 and 9 into contact with said surface. The members 8 and 9 will prevent the two next adjacent type from touching said surface, thus insuring the printing or marking of but one type at a time. The spring metal frame 6 permits the disk to be depressed sufficiently to bring the type into contact with the surface to be printed. Said frame 6 normally holds the disk suspended in spaced relation to the foot plate 7.

The disk 1 is made of spun metal and provided upon its periphery with a flange 14. The type 2 which are preferably of rubber are arranged upon a band 13 which embraces the flange 14 and is cemented thereto. Upon the front face of the disk is secured a ring 15 of cardboard, having characters printed, or formed, thereon corresponding to the type, which assist in selecting any particular type. The ring 15 is covered by a transparent shield 16. Screws 17 and 18 hold the shield 16 and ring 15 upon the face of the disk. The ring 15 is provided with circular slots 19 through which said screws 70 pass, and permit the ring 15 to be rotated so that the position of the characters on the ring may be changed in relation to the type, thus adapting the device for cryptography.

The shaft 3 carrying the disk is positioned, 75 upon the frame 6, at an oblique angle in relation to the foot plate 7, so that the plane of rotation of the disk will be inclined to the foot plate and to the surface to be printed, thus making the characters 80 on the ring 15 easier to read than they would be if the disk were positioned perpendicularly to said surface.

The frame 6, at its lower portion carries a spacing wheel 20, having teeth 21 formed 85 upon its periphery. A bearing plate 22 is formed upon the frame 6 and has a shaft 23 secured therein, on which is rotatably mounted the sleeve 24 forming the hub of the wheel 20. Two teeth of the wheel 20 90 normally rest upon the surface to be printed. By slightly tilting the frame 6 so as to raise the foot plate 7, the wheel 20 may be moved over the surface to be printed one tooth at a time, which movements will represent letter spaces, thus the device may be moved, after each printing of a character the proper spacing distance for the next printing of a character.

The frame 6 has a finger rest plate 25, 100 formed upon the lower portion thereof, adapted to receive the tip of the third finger of the hand when holding the device. Said plate 25 is about the same diameter as the wheel 20 and is adapted to rest upon the 105 surface to be printed when the foot plate 7 is raised.

The frame 6 at its upper portion carries a wire handle, or crotch, 28, having a downwardly curved portion 29 adapted to extend under the palm of the hand with the crotch 28 between the first and second

70 fingers. The free end of the wire is bent upwardly and terminates in a ring 30. The inner end of the wire forming the crotch 28 is provided with a screw-thread 31 which is mounted in a bearing 32 formed upon the frame 6, thus making the height of the crotch 28 adjustable and also permitting the disk to be slightly turned when it is desired to print in italics.

said frame having a portion adapted to rest upon the surface to be printed, a disk, type upon the periphery of the disk, a handle for rotating the disk, a sleeve secured upon the axis of the disk having said handle secured upon the outer end thereof, said sleeve having a threaded aperture formed in the inner end thereof, a sleeve secured in said frame, a shaft loosely mounted in the last mentioned sleeve, a screw thread upon said shaft adapted for adjustably securing the shaft in the sleeve on the disk, a coiled spring mounted upon said sleeves having one end secured to the frame and the other end secured to the disk adapted for rotating the disk to a normal position, and a head on the shaft adapted to limit the longitudinal movement of the shaft through the sleeve of the frame by the action of the 20 spring.

3. A stamping device comprising a frame, said frame having a portion adapted to rest upon the surface to be printed, a disk, type upon the periphery of the disk, a handle for rotating the disk, a shaft mounted upon said frame, said disk rotatably supported upon said shaft, said disk being slidable to and from said frame along the axis of the shaft, a coiled spring tending to force the disk away from the frame and said spring adapted to rotate the disk to a normal position, and a spring plate secured upon the frame adapted to engage the disk when moved along said axis towards the frame.

35 4. A stamping device comprising a frame,

a disk rotatably mounted upon the frame, type upon the periphery of the disk adapted to be moved into contact with a surface to be printed, an ink roller, a bearing upon said frame forming one end of a holder for 40 said roller, a shaft having one end secured in said bearing, a flanged head upon the shaft forming the opposite end of the holder, a sleeve loosely mounted upon said shaft upon which said roller is mounted, and said 45 roller and said type adapted to be brought into contact for inking the type.

5. A stamping device comprising a frame, a disk rotatably mounted upon the frame, type upon the periphery of the disk adapted 50 to be moved into contact with a surface to be printed, an ink roller mounted upon the frame adapted to contact with the face of the type, a sleeve forming the axis of said disk, said sleeve having a chamber adapted 55 to form a reservoir for ink, and a removable plug adapted for closing the end of the sleeve.

6. A stamping device comprising a frame, a disk rotatably mounted upon the frame, type upon the periphery of the disk adapted 60 to be moved into contact with a surface to be printed, a wire forming a crotch, a bearing upon said frame having a threaded aperture adapted to receive one end of said 65 wire and adjustably secure the wire to the frame.

In testimony whereof I affix my signature.

HENRY EMERSON WETHERILL.
